UNITED STATES PATENT OFFICE.

FRED F. HARRIS, OF LOS ANGELES, CALIFORNIA.

GAS-GENERATOR.

1,299,935.

Specification of Letters Patent.

Patented Apr. 8, 1919.

Application filed October 24, 1918. Serial No. 259,524.

To all whom it may concern:

Be it known that I, FRED F. HARRIS, a citizen of the United States, residing at Los Angeles, in the county of Los Angeles and State of California, have invented new and useful Improvements in Gas-Generators, of which the following is a specification.

My invention relates to a burner and more particularly to a gas generating burner.

10 An object of my invention is to provide a simple and serviceable burner for use in a cooking stove or range.

Another object is to provide a burner for use in a stove or range in connection with 15 which kerosene or coal oil may be employed as fuel.

With these and other objects in view my invention consists in the construction, combination and arrangement of parts herein- 20 after described and claimed.

In the accompanying drawings which form a part of this specification.

Figure 1 is a fragmentary view in perspective of a cooking stove provided with 25 a burner embodying the principles of my invention and showing its connections with a kerosene supply tank.

Fig. 2 is an enlarged view in perspective of the burner shown in Fig. 1.

30 Fig. 3 is an enlarged transverse section of the burner shown in Fig. 2, taken on the line 3—3 of Fig. 2.

As shown in Fig. 1, the burner is mounted in a fire box 10 of a stove 11, a supply pipe 35 12 being led into the fire box through holes in the side of the stove and the end plate 13 of the fire box lining. The supply pipe is equipped with a regulating valve 14 and is attached through a needle valve 15 to 40 an oil tank 16. The oil tank is provided with a pressure gage 17 and is connected to an air pump 18 by a tube 19 through a cut-off valve 20. The burner proper comprises a vertical end plate 21 having a straight 45 lower edge or base 22 adapted to rest on the stove grate so that it extends crosswise of the fire box on one end of the grate. The plate is triangular in general form and has annular flanges 23 and 24 formed on its 50 inner face at its ends close to its base and a boss 25 formed on its upward extension 21' midway between its ends. Parallel side tubes 26 and 27 extend lengthwise of the burner and have one end fixed in the annular flanges 22 and 23, these ends being held 55 in the flanges and against the end plate by

set screws in the flanges. The opposite ends of these parallel tubes are connected by an end cross tube 29 having elbow ends 30 and 31 into which the open ends of the parallel tubes 26 and 27 telescope and are held by set screws 31'. The end tube 29 is provided with a base flange 29' on its under side. A vertical tube 32 is joined to the cross tube 29 at its middle. It extends upwardly and terminates in an enlarged right angled elbow 33 having its opening turned toward the end plate 21. A mixing tube 34 made in the form of a right angle elbow has its shorter horizontal extension telescoped 70 into the elbow 33 and held therein by a set screw 35 while its longer vertical extension 36 opens downwardly below the burner. A boss 37 is formed on the outer angle of the elbow so as to face the end plate in horizontal alinement with the boss 25 formed on the upper projection of the end plate. A generating tube 38 extends through the boss 25 in the upper extension 21' of the end plate and is connected to the supply tube 12 by 80 a union 39. The other end of the generating tube extends through the boss 37 formed on the mixing tube 34 and terminates in a mixing chamber 40 within the mixing tube. This end of the generating tube which is 85 held in position by a set screw 41 in the boss 37 is equipped with a cap 42 having a small orifice 43 at its center. This cap and orifice constitute the nozzle of the generating tube. Extending crosswise of the 90 burner between the parallel side tubes 26 and 27 is a series of parallel tubes 44 having their ends fixed in the walls of the side tubes and opening within the tubes. These cross tubes are provided with saw cut openings 45 in their upturned sides which are the gas vents of the burner. A generating trough 46 extends lengthwise of the burner directly under the generating tube 38 and parallel to it between the end plate 21 and 100 the mixing tube 34 resting on the cross tubes 44. A supporting bar 47 extends lengthwise of the burner under the burner tubes directly under the generating trough, one of its ends terminating in a hole 48 in the end plate and the other in a boss 49 formed on the mixing tube. Bolts 50 extending vertically through the supporting bar 47 and the bottom of the generating trough 46 serve to hold the generating trough in place. A 110 shorter supporting bar 51 extends in alinement with supporting bar 47 between the

crosspipe 29 and the mixing pipe 34, its ends terminating in bosses 52 and 53 formed on these tubes in horizontal alinement with each other. The interior of the generating tube is provided with a plurality of straight wires 54 extending lengthwise of the tube, their purpose being to retard the flow of oil through the generator tube and at the same time to provide a relatively large heat 10 retaining substance as well as a large surface in contact with the oil.

Operation: The connections having been made as indicated in Fig. 1, a hand pump 18 is operated to obtain required pressure in 15 the oil tank and valve 20 is closed to retain the air. Mineral wool or some other non-combustible material is placed in the generating trough 46 and alcohol is poured upon it. The alcohol is then lighted and 20 permitted to burn until the heat from the burning alcohol rises against the generating tube and heats it to the required temperature, whereupon the valves 14 and 15 are opened to admit the oil. Oil flows through the generating tube and comes into contact with the heated metal, whereupon it is vaporized. The vapor or gas emerging into the mixing chamber through the orifice 43 with considerable force, draws air upwardly through 25 the open end of the mixing tube and the mixture of air and gas passes through the connecting tube 32, the end tube 29 and the side tubes 26 and 27, thence into the ends of the cross tubes 44 and out through the slots 45 30 where it is burned. The series of cross tubes here provided produces a large and well distributed burning surface especially well adapted for a cooking stove. The generator tube is so placed that, once the burner has 35 been started, the heat of the burner acting upon the generator tube assures the complete vaporization of the oil.

While I have shown the preferred construction of my invention as now known to me, it will be understood that various changes in construction, combination and arrangement of parts may be made by those skilled in the art without departing from the spirit of my invention as claimed.

50 I claim:

1. A gas generating burner comprising a horizontal generator tube adapted to connect with a supply pipe, a mixing tube connected to said generator tube, parallel side tubes 55 fixed in parallel relation to said generator tube, said side tubes having one end closed, connecting tubes between the ends of said

mixing tube and the open ends of said side tubes, a series of cross tubes extending between said side tubes and opening into them, said cross tubes being provided with 60 saw cut openings on their upturned sides and means for initially heating said generator tube.

2. A gas generating burner comprising a vertical end plate, horizontal side tubes having one end fixed in said end plate and closed by it, an end cross tube joining the open ends of said parallel tubes, a vertical branch tube extending upwardly from the middle of said end cross tube, a mixing tube having 65 one end connected to said vertical branch tube and the other open to the air, a horizontal generating tube one end of which opens into said mixing tube and the other end of which extends through said end plate and is 70 adapted to connect with a supply tube, a series of parallel cross tubes extending between said side tubes so that their ends open into said side tubes, said cross tubes being provided with saw cut openings in their upturned sides, means for supporting said series of cross tubes and means for initially 75 heating said generator tube.

3. A gas generating burner comprising a vertical end plate, parallel horizontal side tubes one end of which is fixed in said end plate and is closed by it, an end cross tube connecting the open ends of said parallel side tubes, a vertical branch tube connected to said end cross tube, a mixing tube having 80 one end connected to said vertical branch tube and the other open to the air, a horizontal generating tube one end of which extends through said vertical end plate and is adapted to connect with a supply pipe and 85 the other end of which extends within said mixing tube and is provided with a nozzle, said generating tube having a plurality of wires extending longitudinally through its interior, a generating trough extending between said end plate and said mixing tube in 90 parallel relation to said generating tube, a series of parallel cross tubes extending between said side tubes and having their ends opening into said side tubes, said cross tubes 95 having saw cut openings in their upturned sides to serve as gas vents and a supporting bar extending between said end plate and said end cross tube under and along the middle of said series of cross tubes.

In testimony whereof I have signed my name to this specification.

FRED F. HARRIS.
